UNITED STATES PATENT OFFICE

WILLIAM H. BAYNARD, OF BROOKLINE, MASSACHUSETTS, ASSIGNOR TO HARRY H. BECKWITH, OF BROOKLINE, MASSACHUSETTS.

ADHESIVE-APPLYING DEVICE.

Application filed January 22, 1925. Serial No. 3,956.

This invention relates to devices for applying adhesive, and while not limited in its use thereto, has been more particularly designed to apply latex to shoe stiffeners in order to fix the stiffeners to shoe uppers.

In order that latex may be prevented from coagulating before such coagulation is desired, ammonia is commonly added thereto and in order that the ammonia may not be lost, as well as to prevent discomfort to the operator from the ammonia fumes in the atmosphere, it is important that the supply of latex be closed off from access to the air as much as possible.

In order also that the applying element shall not be soon clogged by the latex coagulating thereon, it is important to protect this element from free exposure to the air and except when actually applying the latex to keep its applying portion submerged in the supply.

It has been found in practice that a brush or roller used in the usual way becomes so clogged with coagulated latex as to become ineffective as an applicator within a few hours after it is first used in case it is exposed in the air.

This invention, therefore, provides a construction in which the latex, or other adhesive, is closed off from access by the air except during those brief periods when application is being made and even then a relatively small quantity is so exposed, and wherein the applicator is submerged except during such brief periods.

It further provides a construction by which the stiffener or other article to which the adhesive is to be applied having been placed on a supporting platform, by a quick in and out motion of the platform by the operator, the receptacle is opened, the applicator is raised from the adhesive to the article on the platform, is caused to apply the adhesive, and is then returned to its submerged condition and the receptacle closed.

For a more complete understanding of this invention reference may be had to the accompanying drawings in which

Figure 1 is a top plan of the device showing a toe stiffener in position thereon preparatory to the application of adhesive thereto.

Figure 2 is a section on line 2—2 of Figure 1.

Figure 3 is a side elevation showing the parts in the same position.

Figure 4 is a fragmentary side elevation showing the adhesive being applied.

Figure 5 is a fragmentary cross section similar to a portion of Figure 2, but illustrating a different adjustment of the parts.

Figure 6 is a sectional detail showing the adhesive being applied.

Referring to these figures, 1 indicates a supporting stand adapted to rest on a suitable bench or table. This stand comprises a shallow receptacle portion formed by means of an elevated base 2 and upwardly extending marginal walls 3. This receptacle is formed with an open topped portion which may be normally covered by a cover member 4. This cover member is formed as an inverted container in which is fixed the adhesive applicator 5 which may comprise a block of sponge rubber of sufficient size to fill the cover and project down into the receptacle beneath the level of the adhesive therein when the cover is closed. The receptacle has a rearward extension 10 having an upstanding circular wall portion 11 defining an opening in which the mouth of an inverted bottle or other similar latex adhesive supply tank 12 may be inserted in such a manner that when such adhesive supply is in position and the cover 4 is closed, the adhesive within the supply and the receptacle is entirely closed off from the external air. In order that this closure may be as complete as possible, it is preferable to place a gasket which may comprise a rubber band as 13 about the supply receptacle 12, this rubber band effecting a seal between the receptacle and the marginal wall 11. By using an inverted supply tank of this type a barometric feed of the adhesive to the forward part of the receptacle in which the applicator 5 dips is effected.

In order that the level of the adhesive in the receptacle may be controlled, even though bottles of various lengths of neck are employed, it is preferable to provide a supply receptacle support adjustable vertically within the extension 10. Such a support is shown at 15 in Figures 2 and 5 and comprises a horizontal annular portion 16 perforated at 17 to receive the neck of the supply bottle and a wall portion 18 which may be fixed in vertically adjusted position to the inner face of the wall 11, as for example 110

by means of a bolt 19 passing through a vertically elongated slot 20 and the wall 11 and threaded into the wall 18. In Figure 2 this support is shown as holding in position a bottle having a relatively long neck, the support being in relatively elevated position, while in Figure 5 a short neck bottle is employed, the support 15 being in a lower position.

- 10 The article to which the adhesive is to be supplied may be supported on a platform 30 which is preferably provided at its forward edge with a hooked finger piece 31 by which it may be grasped and moved as will later appear. This platform 30 is pivoted between the outer spaced ends 32 of an H shaped link 33. The opposite spaced ends of this link are pivoted to lugs 34 extending outwardly in spaced relation from the stand 1. The rear edge of the platform 30 is also pivotally supported from the stand by means of a pair of links 35, the upper ends of which are pivoted at 36 to laterally spaced rearwardly extending ears 37 on the platform 30, these links being pivoted at their lower ends as at 38 to the stand 1. The platform is thus mounted so that it may be positioned forwardly as shown in Figures 1 and 2, or may be pushed rearwardly to take the position over the top of the receptacle as shown in Figure 4. In order that when in this latter position the cover may be raised upwardly and the applicator brought down against an article supported on the platform, the cover 4 is fixed to or integral with the forward ends of a pair of arms 40 fulcrumed at their rear ends as at 41 to the upwardly extending wall 11, and to lugs 45 extending upwardly at opposite ends of this cover are pivoted as at 47 the upper ends of links 46, the lower ends of these links being pivoted to the platform 30 at 36. The links 35 and 46 thus act as toggle links which are straightened during the initial rearward movement of the platform 30 as it is moved to its position over the receptacle, this preliminary movement, therefore, acting to raise the cover 4 so that the platform may pass therebeneath and beneath the applicator 5 carried thereby.
- As the platform is moved still further rearwardly the links 35 and 46 swing beyond their alined positions so that the cover is brought down toward the platform, thus bringing the applicator 5 down into contact with an article supported on the platform. By pulling outwardly on the finger hook 31, the platform is moved outwardly from beneath the applicator whose first motion is upwardly away from the article by reason of the straightening of the links 35 and 46 so that the platform and the article carried thereby are immediately freed from contact with the applicator. As the motion of the platform forwardly is continued it moves

out from beneath the cover 4 which is thereupon returned to closed position by the folding of the toggle link, as shown in Figures 2 and 3, with the applicator dipping beneath the surface of the adhesive within the receptacle and the receptacle entirely closed from access of external air to the adhesive.

As shown best in Figure 6, the stiffener 50 to which the adhesive is applied has its rear edge thinned down, as by skiving, as at 51, consequently the lower face of the applicator is shaped to engage this thin edge being inclined relative to the surface of the table 30 so that the adhesive is applied over this skived portion as well as over that portion where the stiffener is of substantially uniform thickness. The action of the applicator is thus to come down on the stiffener with a nearly direct up and down motion which it is found effectually applies the adhesive thereto and permits free motion of the stiffener to and from adhesive applying position.

Having thus described an embodiment of this invention it should be evident to those skilled in the art that various changes and modifications might be made therein without departing from its spirit or scope as defined by the appended claims.

I claim:

1. A device of the class described comprising a receptacle, a cover for said receptacle, an adhesive applicator carried by said cover, a movable article support, and connections between said support and cover for raising said cover and moving the support beneath said applicator and then lowering said applicator thereon, and for raising said applicator and moving said support from beneath said cover and then closing said cover.

2. A device of the class described comprising a receptacle, a liquid applicator, a movable article support, and means whereby on movement of said support in one direction said applicator moves from said receptacle and applies liquid to an article on said support, and whereby on movement of said support in another direction said applicator returns into said receptacle.

3. A device of the class described comprising a receptacle, a cover for said receptacle, a liquid applicator, a movable article support, and means whereby on movement of said support in one direction said cover is opened and said applicator moves from said receptacle and applies liquid to an article on said support, and whereby on movement of said support in another direction said cover closes.

4. A device of the class described comprising a receptacle, a cover for said receptacle, means for controlling the movement of said cover from and toward its closed position, a pair of toggle links connecting said cover and receptacle on the straightening of

- which said cover is raised, a liquid applicator carried on the inner face of said cover, an article support, links connecting said support to said receptacle, and connections between said support and toggle acting to raise said cover to permit said support to pass thereunder as it moves over said receptacle and to then lower said cover to bring said applicator down toward said support, and to raise said cover to raise said applicator as said support is moved from over said receptacle and to then lower said cover to its closed position with said applicator extending into liquid in said receptacle.
- 5 5. A device of the class described comprising a receptacle, a cover for said receptacle, toggle links pivoted to said receptacle and cover and acting when straightened to hold said cover raised from said receptacle, 65 a support movable toward and from said receptacle, and connections between said support and toggle links acting to straighten them as said support is moved toward said receptacle, permitting said support to pass beneath said cover.
- 10 6. A device of the class described comprising a receptacle, a cover for said receptacle, a liquid applicator fixed to the lower face of said cover, toggle links pivoted to 70 said receptacle and cover and acting when straightened to hold said cover raised from said receptacle, a support movable toward and from said receptacle, and connections between said support and toggle links acting to straighten 75 said toggle links to raise said cover as said support is moved toward said receptacle permitting said support to pass beneath said cover, further motion of said support after the straightening of said toggle links acting to lower said cover and to bring said applicator against an article placed on said support.
- 15 7. A device of the class described comprising a receptacle having a rearward extension shaped to receive and enclose thereto a bottle in inverted position to feed a liquid barometrically to said receptacle, a cover for said receptacle in front of said extension, a liquid applicator carried on the inside of 80 said cover and dipping into the liquid therein when the cover is closed, and means by which the cover may be raised to permit an article to be moved thereunder and into contact with said applicator.
- 20 8. A device of the class described, comprising a receptacle having a rearward extension shaped to receive and enclose a bottle in inverted position to feed a liquid barometrically to said receptacle, a cover for 85 said receptacle in front of said extension, a liquid applicator carried on the inside of said cover and dipping into the liquid therein when the cover is closed, a movable article support, and means for raising said applicator out of said liquid and for bringing the article on said support into contact with said applicator while out of said liquid.
- 25 9. A device of the class described, comprising an open-topped receptacle having a rearward extension, a holder for an inverted bottle in said extension adjustable to regulate by barometric pressure the level of liquid flowed from said bottle into said receptacle, a cover for said receptacle in front of said extension, and a liquid applicator 90 carried on the inside of said cover and dipping into the liquid therein when the cover is closed, a movable article support, and means for raising said applicator out of said liquid and for bringing the article on said support into contact with said applicator while out of said liquid.
- 30 10. A device of the class described, comprising a receptacle having a rearward extension formed with an upstanding marginal wall shaped to receive and support a bottle in inverted position therein, an annular support for the neck of the bottle and against which the portion below said neck engages vertically adjustable relative to said extension to determine the height of said bottle mouth in the base of said receptacle, a cover for said receptacle in front of said extension, a liquid applicator carried on the inside of said cover and dipping into the liquid therein when the cover is closed, a movable article support, and means for raising said applicator out of said liquid and for bringing the article on said support into contact with said applicator while out of 95 said liquid.
- 35 11. A device of the class described, comprising a receptacle having a rearward extension shaped to receive and enclose a bottle in inverted position to feed a liquid barometrically to said receptacle, a cover for 100 said receptacle in front of said extension, an applicator on the inside of said cover and dipping into the liquid in said receptacle, a movable article support, and connections between said cover and support, by which said cover may be raised and said applicator applied to an article on said support, said cover when closed and said bottle together closing off the liquid in said device from access of 105 external air thereto.
